UNITED STATES PATENT OFFICE.

LOUIS COHEN, OF WASHINGTON, DISTRICT OF COLUMBIA.

ELECTRICAL SIGNALING.

Application filed January 16, 1922. Serial No. 529,686.

To all whom it may concern:

Be it known that I, LOUIS COHEN, residing in Washington, District of Columbia, have invented certain new and useful Improvements in Electrical Signaling, of which the following is a specification.

This invention relates to the art of radio signaling and particularly to improvements in receiving radio signals and a system for 10 use in practicing the same.

The object of the present invention is to eliminate interference and electro-static disturbances in the reception of radio signals, and thus improve the clearness and reliability of radio communication.

The method involved consists in the use of a sectional wave conductor as part of the antenna circuit. This sectional wave conductor is preferably made in the form 20 of one or more long helices wound with copper wire in single or multiple layers, parts of the system of wave coils being enclosed in metal tubes which are in electrical connection at one point with the wave coil. 25 The electrical constants of the wave coils, inductance, capacity and resistance, are distributed in character, but the capacity of the sections of the wave coils which are enclosed in the metal tubes is different from 30 the capacity of the sections of the wave coils which are free, and hence the system of wave coils has different wave propagation characteristics for the different parts and is therefore, the equivalent of a sectional wave conductor. Each metal tube is 35 also grounded through a loop circuit consisting of an inductance and capacity in parallel. By adjusting the electrical constants, inductance and capacity of the loop 40 circuit, so as to bring it into resonance for the frequency of the signal which it is desired to receive, it has the equivalent effect of a very high resistance in the circuit between the metal tube and ground for currents of that particular frequency, and as a 45 consequence, the capacity currents from the wave coil to the tube will find their way back into the wave coil at the point of connection between the metal tube and the wave 50 coil, since there is a difference of potential between the point on the wave coil where the connection is made to the metal tube and the parts of the wave coil enclosed in the metal tube. Very little of the capacity

current will leak away to ground since the 55 loop circuit has the equivalent effect of a very high resistance for the frequency of the signal it is desired to receive. To be sure a small amount of current leakage to ground will occur due to the capacity of the 60 metal tube to ground, but this will be small compared to the capacity current flow to the coil at the point of connection of the metal tube. As a result of this, it can be shown theoretically, that the part of the wave coil 65 which is enclosed in the metal tube acts like a lumped inductance shunted by a capacity, simply introducing an additional impedance in the antenna circuit. By properly adjusting the length of the wave coil 70 enclosed in the metal tube, the position and connection of the metal tube on the wave coil, the total impedance of the antenna circuit including the antenna, any intermediate 75 inductance and capacity, and the part of the wave coil enclosed in the metal tube, may be reduced to a minimum and thereby obtain a relatively large signal current at the point where the metal tube is connected to the wave coil, and from there on the signal 80 current is propagated along the rest of the wave coil in the form of a wave which is detected at a suitable point on the wave coil by the usual detecting instrumentalities.

For any other electrical effects acting on the antenna which may be due to interfering signals or static disturbances, the loop circuit no longer functions as the equivalent of a high resistance, and therefore most 90 of the capacity current from the wave coil to the metal tube finds its way direct to ground through the loop circuit, with the result that the interfering electrical effects are propagated along that part of the wave 95 coil enclosed in the metal tube, as well as the rest of the wave coil, in the form of a wave which is attenuated as it progresses along its path. Also a large part of the current flow in the coil will find its way 100 to ground at the junction point where the metal tube is connected to the coil because of the low resistance loop circuit path. Further, the two parts of the wave coil, one 105 of which is enclosed in the metal tube and the other which is free, have different electrical characteristics, particularly the capacity constants, and therefore the wave

undergoes a reflection at the junction of these two sections of the wave coil which serves to still further reduce the intensity of the wave in its progress along the entire 5 wave coil. It is evident that this method offers a means for rendering the reception of radio signals free from interfering effects by rapidly damping out the others by leakage, reflection and attenuation.

10 It is obvious that by the use of several sections, the alternate parts of which are enclosed in metal tubes and grounded through separate loop circuits, a still greater 15 advantage may be gained in the matter of reducing interfering effects on the detecting instrument.

The principle of operation and the method 20 of using this invention can be better understood by reference to the accompanying dia- grammatic figures which show typical em- bodiments of the invention and form part of this specification.

In the accompanying drawings:

25 Figure 1 is a diagrammatic view of a system for carrying out the invention in which a single metal tube covering one section of the wave coil is used.

Figure 2 is a modification in which two 30 separate metal tubes enclosing different parts of the wave coil are employed.

Figure 3 is an arrangement in which a loop antenna, a wave coil and one metal tube is used.

Having more particular reference to the 35 drawings, and in connection with which like characters of reference will designate corresponding parts throughout, in Figure 1, the antenna 1 is connected to a variable condenser 2 and the wave coil 3, 10 all in series: 40 the metal tube 4 is connected to the wave coil at the point 9 and is also grounded at 8 through the connection 5 and loop circuit 7, 6. The metal ring 11 constitutes an elec- 45 tro-static connection to the grid of a three- electrode vacuum tube detector 14 to the wave coil 10. The circuit 12, 13 together with the regenerative coupling coil 15, is 50 for the purpose of generating oscillations of a different frequency from that of the incoming signals and by combining the effects on the detector beats are produced giving an audible note which is heard in the telephone 16.

The operation is as follows: The loop 6, 55 7, is adjusted to be in resonance for the frequency of the signals to be received and gives thereby the equivalent effect of a very high resistance in the circuit 5, 6, 7, 8, for that particular frequency, and, as a conse- 60 quence, the capacity currents from the portion 3 of the wave coil to the metal tube 4 flow towards 9 and then in the coil portion 10 in the form of a wave, since the coil portion 10 has distributed inductance and 65 capacity, the capacity being principally the

capacity of the coil to ground. The part of the wave coil portion 3 which is enclosed in the metal tube 4 acts in this case as the equivalent of a lumped inductance shunted by a capacity, the capacity being that between the coil and the metal tube and has therefore, the same effect as that of an impedance in the antenna circuit, which may be a somewhat complicated function of the inductance, capacity and frequency. By prop- 70 erly adjusting the variable capacity 2, length of the end of the coil portion 3 which is not enclosed in the tube, the length of the tube, all in relation to the antenna, the fre- 75 quency of the signal and the size of the wave coil employed, the total impedance of the antenna circuit up to the junction point 9 may be made a minimum, thereby enhanc- 80 ing the signal effect which from that point on is propagated on the balance of the wave coil portion 10, and detected through the electro-static connection 11.

For any other electrical effects acting on the antenna which may be due either to interfering signals or electro-static disturbances, the circuit 5, 6, 7, 8, acts as a low 90 resistance leak to ground, and therefore the part of the wave coil portion 3 which is enclosed in the metal tube 4 no longer acts as the equivalent of a lumped inductance 95 shunted by a capacity as in the case of the signal frequency, but rather as a distributed inductance and capacity. In this case the capacity current from the wave coil to the metal tube flows direct to ground, since the 100 loop circuit has a small resistance for any frequency differing from the frequency for which the circuit is tuned. The undesirable 105 electrical disturbances are propagated on the wave coil enclosed in the metal tube as well as on the balance of the wave coil ex- 110 tending beyond the metal tube in the form of a wave which is attenuated in its travel along the entire wave coil. We have, there- 115 fore, a condition where foreign disturbances travel in the form of waves over consider- ably longer conductors and are therefore at- 120 tenuated to a much greater extent than the signals desired to be received. Also foreign disturbances traveling along the coil por- 125 tion 3 have a low resistance path through the loop circuit when it reaches the junction point 9, and therefore a considerable part of that current is shunted away to ground at that point and only a relatively small 130 part of that current is transmitted to the balance of the wave coil extending beyond the junction point 9. Further for foreign disturbances, we have in this arrangement, the equivalent condition of two conductors of different distributed electrical characteristics, the capacity per unit length of the part of the wave coil which is enclosed in a metal tube being greater than the capac- ity per unit length of the wave coil which

- extends beyond the metal tube. Also, the inductance per unit length of the two sections of the wave coil may be made different if desired, but in any case, because of the 5 difference in the electrical characteristics, a reflection of the wave occurs at the junction point thereby further reducing the effects of the disturbances which are transmitted on the balance of the wave coil portion 10. 10
- 10 Due to the combination of all these contributing factors mentioned above, leakage, reflection, attenuation, very little if any of interfering disturbances can reach the far end of the wave coil portion 10 to affect the 15 detector.
- Figure 2 is a modification in which two different sections of the wave coil are enclosed in two separate metal tubes 4 and 4' each metal tube being grounded through a 20 separate loop circuit 5, 6, 7, 8 and 5', 6', 7', 8', respectively, thereby effecting a progressive reduction in foreign disturbances. All the statements made above in connection with Figure 1 apply in this case to each of 25 the two separate sections enclosed in the different metal tubes and any residual effect which may find its way into the coil beyond that part enclosed in the metal tube 4 is still further reduced in its passage along the section 30 of the wave coil which is enclosed in the metal tube 4' thus offering a means for still further reducing interfering effects in the reception of radio signals. In this figure the detector is directly connected to the 35 wave coil portion 10 at the point 24.
- Figure 3 is an embodiment of this invention in which a loop antenna is employed. The antenna circuit 22, 23 is tuned to the frequency of the signals to be received, and the 40 potential of condenser 23 is impressed on the wave coil 3, 10 effecting a wave development on it, the principle of operation being the same as that described in connection with the other two figures.
- 45 It is obvious that various modifications may be made without departing from the spirit of the invention. The detector connection may be either direct or electro-static in all of the figures, but for purposes of 50 illustration a direct connection is shown in one figure and an electro-static connection in the other two figures. Also the loop circuit may be connected directly to the metal tube as shown in the figures or through an 55 intermediate impedance, preferably a condenser. Also one form of a three electrode detector circuit is shown in all the figures but any other form of detector or detector circuit may be employed. It is obviously 60 within the province of this invention to introduce these variations.

I claim:

1. In a system for radio signaling comprising an antenna, wave coil, part of said wave coil being enclosed in an adjustable 65

metal tube, said metal tube being electrically connected to a point on the said wave coil, and also being grounded through a loop circuit, and detecting instruments associated electrically with said wave coil. 70

2. In a system for radio signaling comprising an antenna, wave coil, a variable condenser, part of said wave coil being enclosed in an adjustable metal tube, said metal tube being connected electrically to a point on the said wave coil, and also being grounded through a loop circuit and detecting instruments associated electrically with said wave coil. 75

3. In a system of radio signaling comprising an antenna, variable condenser, wave coil, part of said wave coil being enclosed in an adjustable grounded metal tube, said metal tube being connected electrically to a point on the said wave coil, and also being grounded through a loop circuit, said loop circuit being adjusted to be in resonance for the frequency of the signals to be received, and a detecting instrument associated electrically with the said wave coil. 80 85 90

4. In a system of radio signaling comprising an antenna, variable condenser, wave coil, part of said wave coil being enclosed in an adjustable grounded metal tube, said metal tube being connected electrically to a point on the said wave coil, and also being grounded through a loop circuit, said loop circuit being adjusted to be in resonance for the frequency of the signals to be received and a detecting instrument associated electro-statically with the said wave coil. 95 100

5. A system of radio signaling comprising an antenna, a variable condenser, a wave coil, sections of said wave coil being enclosed in separate metal tubes, said metal tubes being electrically connected at different points to the said wave coil, and also being separately grounded through separate loop circuits, and a detecting instrument connected electrically to said wave coil. 105 110

6. A system of radio signaling comprising an antenna, a variable condenser, a wave coil, sections of said wave coil being enclosed in separate metal tubes, said metal tubes being connected electrically at different points to the said wave coil, and also being separately grounded through separate loop circuits, each of said loop circuits being separately tuned to be in resonance for the frequency of the signal desired to be received, and a detecting instrument connected electrically to said wave coil. 115 120

7. In a system of radio signaling comprising a loop antenna, variable condenser, wave coil, part of said wave coil being enclosed in an adjustable grounded metal tube, said metal tube being connected electrically to a point on the said wave coil and also being grounded through a loop circuit, said loop circuit being adjusted to be in resonance 125 130

for the frequency of the signals to be received and a detecting instrument associated electrically with the said wave coil.

8. A system of radio signaling comprising a loop antenna, a variable condenser, a wave coil, sections of said wave coil being enclosed in separate metal tubes, said metal tubes being connected at different points to

the said wave coil and also being separately grounded through separate loop circuits, each of said loop circuits being separately tuned to be in resonance for the frequency of the signal desired to be received, and detecting instruments connected electrically to said wave coil.

LOUIS COHEN.
